UNITED STATES PATENT OFFICE.

JOHN GALBRAITH, OF SWATARA, MINNESOTA, ASSIGNOR OF ONE-HALF TO FRANK J. WIDMAN, OF CHICAGO, ILLINOIS.

WOOD-CARVING MACHINE.

1,229,059.

Specification of Letters Patent.

Patented June 5, 1917.

Application filed May 10, 1916. Serial No. 96,664.

To all whom it may concern:

Be it known that I, JOHN GALBRAITH, a citizen of the United States, residing at Swatara, Aitkin county, Minnesota, have invented certain new and useful Improvements in Wood-Carving Machines, of which the following is a specification.

The present invention has to do with improvements in wood carving machines, and has particular reference to improvements in that type of wood carving machine in which the replica is carved during the movement of a tracer over the surface of the model. In machines of this type there is provided a tracing point or the like which can be moved in any desired direction back and forth over the surface of the model, the tracing point also rising and falling according to the irregularities or changes in elevation of the different portions of the surface of the model, and there is also provided one or more carving tools which simultaneously follow the movements of the tracing point. The movements of the carving tools may be of equal magnitude with the movements of the tracing point, in which case the replica or replicas will be of the same size as the model, or there may be either a magnification or diminution of size of the replica as compared to that of the model.

In order that machines of this type may be entirely satisfactory for the purpose intended, they should be so constructed that very delicate or slight changes in the position of the tracing point, either horizontally or vertically, will be accurately transmitted to the carving tool or tools. Furthermore, such machines should be very delicately balanced in order that they may be properly manipulated by the operator without jerking or violent fluctuations.

One of the objects of the present invention is to so construct the mechanism of the carving machine as to very accurately reproduce the movements of the tracing point in the movements of the carving tools, while at the same time providing a machine of great strength and permanency.

Another object of the invention is to so construct the machine that the same will be maintained in balance at all positions of the tracing point and carving tools within all

reasonable ranges of movement of these parts during the carving operation.

Another object of the invention is to provide a machine of very simple construction and one which can be manufactured and assembled at a comparatively small cost. In this connection another object is to so construct the machine that all of the movements may be secured with a minimum number of links and moving parts.

Other objects and uses of the invention will appear from a detailed description of the same, which consists in the features of construction and combinations of parts hereinafter described and claimed.

Referring to the drawings:

Figure 1 shows a front elevation of the assembled machine;

Fig. 2 shows a side elevation of the assembled machine;

Fig. 3 shows a plan view corresponding to Figs. 1 and 2;

Fig. 4 shows a fragmentary side elevation of the upper operating portion of the machine, the tracing point and carving tools being moved backwardly and upwardly from the position shown in Fig. 2;

Fig. 5 shows a fragmentary plan view corresponding to Fig. 4; and

Fig. 6 shows a fragmentary vertical cross-section taken on the line 6—6 of Fig. 2, looking in the direction of the arrows.

In the several figures I have shown the features of my invention as being incorporated within a machine having a fixed table for the support of the model and the replicas, but I desire to state at this point that said features are in no wise limited to use in connection with such a table, inasmuch as any other suitable support for these parts might be substituted for such table.

Referring now to the several figures, the machine is shown as being supported by a frame-work including the side brackets 7 and 8 and the cross rods 9. Connected to the brackets 7 and 8 are the lugs or projections 10, which are mounted in pairs standing in vertical alinement. Extending through the lugs 10 at each corner of the machine is a vertically adjustable post 11, the posts at each side of the machine carrying a longitudinally extending rail or the

like 12. The table proper comprises a series of cross slats 13 mounted upon the rails 12, to which slats may be bolted or otherwise secured the model and the replicas.

5 Each of the posts 11 has its lower portion threaded, and a sprocket wheel or the like 14 is threaded on each of said posts and rests against the lowermost lug 10, through which said post extends. A chain 15 completely 10 encircles the frame, said chain riding on all of the sprocket wheels at the four corners. By pulling the chain in the one direction or the other, the table may be raised or lowered to secure vertical adjustment.

15 At each side of the machine is an upstanding bracket 16, these two brackets together serving to carry the operative mechanism. The brackets are conveniently joined together in their upper forward portions by 20 a pair of crosswise extending tubes 17 and 18, which tubes are clamped to the brackets. Such clamping is conveniently effected by means of a removable cap 19, on each of the brackets. Another crosswise extending bar 25 or the like 20 preferably connects together the rear upper portions of the brackets and serves as a convenient mounting for certain of the operative elements.

30 Downwardly depending from the central portions of the tubes 17 and 18 is a bracket 21 which is rigidly connected to said tubes. The lower end of this bracket 21 is inturned to provide a journal 22 in vertical alignment with another journal 23, also carried 35 by said bracket 21. A vertical shaft 24 is mounted in the bearings 22 and 23. The shaft 24 serves as a convenient center for the support of certain of the operating elements of the machine.

40 Swingly mounted on the shaft 24 are the sidewise extending yokes 25 and 26, best shown in Fig. 1. Each of these yokes has its inner end bifurcated and swung on the shaft, so that the outer ends of said yokes 45 may be swung back and forth. The yokes are supported by the lower bearing 22 of the bracket 21, by which bearing they are prevented from dropping off from the lower end of the shaft.

50 Swiveled on the outer ends of the yokes 25 and 26 are the universal brackets 27 and 28 respectively. Each of these universal brackets comprises a vertical member 29 having the forwardly extending upper and 55 lower arms 30 and 31 respectively, and the forwardly extending central arm 32. Sidewise projecting from the central arm 32 is the boss 33. The bosses of the universal brackets 27 and 28 are swiveled to the end 60 portions of the respective yokes 25 and 26 by means of the studs 34. It, therefore, follows that each of the universal brackets may have a rocking motion on its stud with respect to the corresponding yoke, but that 65 each universal bracket is compelled at all

times to lie in a plane at right angles to its yoke during the back and forth movements of such yoke and during the swinging or swiveling movements of the universal bracket on its stud.

70 In the rear portion of the machine is a floating bar 35. The said floating bar may rise and fall or move back and forth freely, according to the movements of the tracing point and carving tools. This floating bar is, however, prevented from swaying sidewise, so that each point in its length always travels within the same vertical plane extending longitudinally of the machine. For this purpose I have shown a pair of downwardly depending arms 36, the upper ends of said arms being connected to a bracket 37 which is carried by the cross pin 20, but cannot move sidewise across the machine. The lower portion of each arm 36 is thus caused to 80 swing within a plane surface. Connected to the lower ends of the arms 36 are the forwardly extending arms 38. The arms 36 and 38 are connected together by the brackets 39 and 40, and the front ends of the arms 38 are connected to the floating bar 35 by the brackets 41. Consequently the floating bar cannot move laterally or sidewise without distorting the arms 36 and 38. The floating bar can, however, move back and 90 forth and up and down in the manner previously described.

95 Extending between the universal brackets 28 and 29 and the floating bar are the bifurcated yokes 42 and 43 respectively. The forward end of each of these yokes has the forwardly extending arms 44 and 45, which embrace the corresponding universal bracket, and the rear end of each bifurcated yoke is pivoted to the floating bar by means 105 of a pin 46. The pins 47 and 47^a serve as pivotal connections between each universal bracket and the corresponding bifurcated yoke. Each of these pins has its inner end provided with a bearing for a shaft 47^b 110 which extends through the arm 32 of the corresponding universal bracket. It, therefore, follows that during the back and forth movements of the floating bar each bifurcated yoke is enabled to swing with respect 115 to the corresponding universal bracket while permitting the said universal bracket to maintain its position of right angularity with respect to the corresponding yoke 25 or 26.

120 Forwardly extending from the floating bar are the brackets 48 and 49, said brackets having their rear ends rigid with respect to the floating bar. Swiveled onto the forward end of the brackets 48 and 49 are the bifurcated arms 50 and 51 respectively, said arms being swiveled to their respective brackets by the vertical pins 52 and 53 respectively. Extending between the front ends of the bifurcated arms 50 and 51 is the control bar 130

54, which carries the tracing point and the carving tools. The end portions of this control bar are connected to the bifurcated arms 50 and 51, said connections being a fixed 5 distance apart equal to the distance between the rear ends of said bifurcated arms. Consequently, the control bar may be moved laterally, the bifurcated arms 50 and 51 swinging on their pivotal points 52 and 53 without 10 any movement of the brackets 48 and 49. On the other hand, the back and forth movement of the control bar will serve to cause the floating bar to move back and forth synchronously.

15 The studs 34 by which the universal brackets are connected to the yokes 25 and 26 serve as centers about which the control bar may be raised and lowered with a swinging motion. If the control bar be raised, 20 the floating bar will be forced downwardly, both of these parts moving in arcuate fashion with respect to the studs 34. By reason of the interposition of the universal brackets between the bifurcated yokes 42 and 43 25 and the yokes 25 and 26, it follows that the control bar may be raised and lowered in the foregoing manner regardless of its position longitudinally of the machine.

Inasmuch as the bifurcated arms 50 and 30 51 and the control bar extend forwardly with respect to the studs 34, while the remaining mechanisms lie to the rear of said studs, it follows that there will be a counter-balancing action. Ordinarily this will tend 35 to cause all of the parts to float during their movements, so that the control bar may be manipulated by the operator with a minimum exertion. Ordinarily it is desirable to cause the bifurcated arms and control bar 40 to slightly overbalance the other mechanisms, so that there will be a slight tendency for the control bar to fall. In order to secure a very nice adjustment of balance, a pin 55 may be extended rearwardly with respect to the floating bar, and a counter-balance 45 56 may be slidingly mounted on said pin so as to permit the securing of very nice adjustments of balance.

The tracing point 57 is conveniently 50 mounted on the central portion of the control bar. At suitable points within the length of the control bar are the carving tools 58. In the construction illustrated I have shown four of said carving tools, although manifestly a greater or lesser number may be adopted as desired. Each of the carving tools comprises a bit of well known construction driven at high speed, and I do not here concern myself particularly with 55 the construction of these tools. Suffice it to say at this point that the tools are to be driven at high speed and that their lower cutting ends should preferably lie in exact alinement with the lower end of the tracing point.

In order to permit the tracing point and carving tools to be thrown into different positions I have shown the control bar as being pivoted to the forward ends of the bifurcated arms 50 and 51 by means of the pins 59 and 60. This construction permits the control bar to be rotated about a horizontal axis.

Any suitable means may be adopted for driving the carving tools at the desired speed. For example, independent driving motors or the like might be used for this purpose. I have, however, illustrated a single motor for driving all of the carving tools from a center point. For this purpose I have shown the motor 61 as being mounted on the upper end of the shaft 24 and driving said shaft. The said shaft carries the pulleys 62 and 63 at points intermediate the inner bifurcated ends of the yokes 25 and 26. The shafts 47^b carry the pulleys 64 and 65 corresponding to the pulleys 62 and 63 respectively. The belts 66 and 67 serve to drive the shafts 47^b through the medium of said pulleys.

Each of the carving tools is driven by a pulley 68 working within a slot of the control bar. The lower portion of each of the shafts 47^b carries a pulley 69 driving a forwardly extending belt 70. The belts 70 extend around the pulleys 68 of two of the carving tools, so that each of the pulleys 69 drives two of said tools. A slack take-up device 71 is provided for each of the belts 70, said take-up device including a bell crank having a pair of pulleys 72 and 73 working on opposite sides of the belt, a spring 74 tending to tilt the bell crank so as to keep the belt under tension at all times.

Inasmuch as the shafts 47^b always maintain a fixed distance from the driving shaft 24 it follows that the belts 66 and 67 will always remain under tension no matter what the position of the control bar may be. Therefore, by maintaining the belts 70 always under tension it follows that power will always be transmitted simultaneously to all of the carving tools in all positions of the control bar.

It will be observed from a study of the herein disclosed constructions that during all of the movements of the control bar 54, said bar is compelled to lie in the same direction, so that it always maintains a position of parallelism with respect to its previous positions. This result follows by reason of the fact that the pivotal points 52 and 53 are separated such a distance from each other that the bifurcated arms 50 and 51 always maintain a condition of parallelism. It will also be observed that in the raising and lowering of the control bar, the same swings about an axis extending through the studs 34. Inasmuch as the universal brackets 27 and 28 are enabled to rock on the said

studs, it follows that the said swiveling of the control bar about the said axis takes place regardless of the exact position of the control bar in a direction back and forth along the machine. Furthermore, the counter-balancing effect is also present at all times and always to an equal degree.

While I have herein shown and described only a single embodiment of my invention, still it will be understood that I do not in anywise limit myself to the said embodiment, except as I may do so in the claims.

I claim:

1. In a carving machine, the combination with a suitable framework, of a vertically extending axial member connected to the same, a pair of sidewise extending yokes on the same, a universal bracket swiveled on the end portion of each of said yokes, a floating bar, a bifurcated yoke on each universal bracket, a pivotal connection between the rear end of each bifurcated yoke and the floating bar, a pivotal connection between the front end of each bifurcated yoke and the corresponding universal bracket, means for retaining the floating bar against lateral displacement while permitting each portion of said bar to move freely in a vertical plane, a pair of forwardly extending brackets having their rear ends rigidly connected to the floating bar, a bifurcated arm swiveled on the forward end of each of said brackets, a control bar pivotally connected to the forward ends of said bifurcated arms, the said bifurcated arms lying parallel to each other, a tracing point on the control bar, suitable carving tools on the control bar, and means for driving the said carving tools in any position of the control bar, for the purpose specified.
2. In a carving machine, the combination with a suitable framework, of a vertically extending axial member carried by the framework, a pair of sidewise extending yokes swiveled on said axial member, a universal bracket swiveled on the outer extremity of each sidewise extending yoke, a floating bar lying to the rear of the sidewise extending yokes, a pair of bifurcated yokes having their rear ends pivoted to the floating bar and their forward ends pivoted to the universal brackets, a forwardly extending bracket on each side of the machine, each of said brackets having its rear end rigidly connected to the floating bar, a bifurcated arm pivotally connected to the forward end of each of said brackets, said bifurcated arms lying parallel to each other, a control bar pivotally connected to the forward ends of the bifurcated arms, a tracing point on the control bar, a suitable carving tool on the control bar, and means for driving said carving tool in any position of the control bar, for the purpose specified.
3. In a carving machine, the combination

with a suitable framework, of a vertically extending axial member carried by the framework, a pair of sidewise extending yokes swiveled on said axial member, a universal bracket swiveled on the outer end of each of said yokes, a floating bar lying to the rear of said yokes, a bifurcated yoke in each side of the machine, each bifurcated yoke having its rear end pivoted to the floating bar and its forward end pivoted to the corresponding universal bracket, a pair of forwardly extending brackets having their rear ends rigidly connected to the floating bar, a pair of bifurcated arms having their rear ends pivoted to the forward ends of the said brackets, the said bifurcated arms always lying parallel to each other, a control bar pivotally connected to the forward ends of the bifurcated arms, an adjustable counter-balance on the floating bar, a tracing point on the control bar, a suitable carving tool on the control bar, and means for driving said carving tool in any adjusted position of the control bar, for the purpose specified.

4. In a carving machine, the combination with a suitable framework, of a vertically extending axial member carried by the framework, a pair of sidewise extending members pivotally mounted on said axial member, a universal bracket on the outer end of each of said sidewise extending members, a floating bar to the rear of the sidewise extending members, a link connection from each universal bracket to the floating bar, a forwardly extending member in each side of the machine, each of said forwardly extending members having its rear end rigidly connected to the floating bar, a bifurcated member corresponding to each of the said forwardly extending members, a pivotal connection between each bifurcated member and the corresponding forwardly extending member, the forwardly extending members lying parallel to each other, a control bar, pivotal connections from the control bar to the bifurcated members, a tracing point on the control bar, a suitable carving tool on the control bar, and means for driving said carving tool in any adjusted position of the control bar, for the purpose specified.

5. In a carving machine, the combination with a suitable framework, of a vertically extending axial member, a pair of sidewise extending members pivoted to said axial member, a floating bar lying to the rear of the sidewise extending members, a pair of bifurcated yokes, a pivotal connection between each bifurcated yoke and the floating bar, a universal connection between each bifurcated yoke and the corresponding sidewise extending member, a forwardly extending member in each side of the machine, a rigid connection between each forwardly ex-

6. In a carving machine, the combination with a suitable framework, of a vertically extending axial member, a pair of sidewise extending members pivoted on said axial member, a floating bar to the rear of said sidewise extending members, a universal connection between the floating bar and each sidewise extending member, a forwardly extending member in each side of the machine, a rigid connection between each forwardly extending member and the floating bar, a bifurcated arm in each side of the machine, a pivotal connection between each bifurcated 20 arm and the corresponding forwardly extending member, a control bar, a pivotal connection from the control bar to each bifurcated arm, a tracing point on the control bar, a suitable carving tool on the control bar, and means for driving said carving tool in any adjusted position of the control bar, for the purpose specified.

7. In a carving machine, the combination with a suitable framework, of a vertically extending axial member, a pair of sidewise extending members swiveled on said axial member, a floating bar lying to the rear of the sidewise extending members, a universal connection between the floating bar and each sidewise extending member, means for retaining the floating bar against lateral displacement while permitting each point of said bar to move freely within a vertical plane, a forwardly extending member in each side of the machine, a rigid connection between the rear end of each of said members and the floating bar, a bifurcated arm in each side of the machine, a pivotal connection between each bifurcated arm and the corresponding forwardly extending member, a control bar, a pivotal connection between the control bar and each of the bifurcated arms, an adjustable counter-balance on the floating bar, a tracing point on the control bar, a suitable carving tool on the control bar, and means for driving said carving tool in any adjusted position of the control bar, for the purpose specified.

8. In a carving machine, the combination with a suitable framework, of a vertically extending axial member, a pair of sidewise extending members pivotally mounted on said axial member, a floating bar lying to the rear of the sidewise extending members, a universal connection between the floating

bar and each sidewise extending member, a control bar in the forward portion of the machine, a swiveled connection between each end of the control bar and the floating bar, an adjustable counter-balance on the floating 70 bar, a tracing point on the control bar, a suitable carving tool on the control bar, and means for driving said carving tool in any adjusted position of the control bar, for the purpose specified.

9. In a carving machine, the combination with a suitable framework, of a pair of sidewise extending members, a pivotal connection between each sidewise extending member and the framework, whereby each of said members is permitted to swing about a vertical axis, a floating bar lying to the rear of the sidewise extending members, a universal connection between the floating bar and each sidewise extending member, a control bar in 80 the forward portion of the machine, a pivotal connection between each end of the control bar and the floating bar, an adjustable counter-balance on the floating bar, a tracing point on the control bar, a suitable carving 90 tool on the control bar, and means for driving said carving tool in any adjusted position of the control bar, for the purpose specified.

10. In a carving machine, the combination with a suitable framework, of a pair of sidewise extending members, a pivotal connection for each of said members whereby the same is enabled to swing about a vertical axis, a floating bar to the rear of the sidewise extending members, a universal connection between the floating bar and each sidewise extending member, means for retaining the floating bar against lateral displacement while permitting each point on 105 said floating bar to move freely within a vertical plane, an adjustable counter-balance on the floating bar, a control bar in the forward portion of the machine, a pivoted connection between each end of the control bar 110 and the floating bar, whereby the control bar is enabled to move laterally with respect to the floating bar while remaining parallel to the floating bar, a tracing point on the control bar, a suitable carving tool on the control bar, and means for driving said carving 115 tool in any adjusted position of the control bar, for the purpose specified.

11. In a carving machine, the combination with a suitable framework, of a pair of sidewise extending members, a pivotal mounting for each of said members whereby the same is enabled to swing about a vertical axis, a floating bar behind the said members, a universal connection between the 120 floating bar and each of said members, a control bar in the forward portion of the machine, a pivotal connection between each end of the control bar and the floating bar, whereby the control bar is enabled to move 125 130

laterally with respect to the floating bar, while remaining parallel to the floating bar, a tracing point on the control bar, a suitable carving tool on the control bar, and means for driving said carving tool in any adjusted position of the control bar, for the purpose specified.

12. In a carving machine, the combination with a suitable frame-work, of a pair of 10 sidewise extending members, a pivotal connection between each sidewise extending member and the frame-work, whereby each of said members is permitted to swing about a vertical axis, a floating bar, a universal connection between the floating bar and each 15 sidewise extending member, a control bar in the forward portion of the machine, a pivotal connection between each end of the control bar and the floating bar, a tracing

point on the control bar, a suitable carving 20 tool on the control bar, and means for driving said carving tool in any adjusted position of the control bar, for the purpose specified.

13. In a carving machine, the combination with a suitable frame-work, of a pair of 25 members, each member being pivoted on a vertical axis, a floating bar, a universal connection between the floating bar and each of 30 said members, a control bar, a pivotal connection between each end of the control bar and the floating bar, a suitable carving tool on the control bar, and means for driving said carving tool in any adjusted position of the control bar, for the purpose specified.
